United States Patent Office

Des. 185,514
Patented June 16, 1959

185,514

LABEL

George R. Ryan, Waukegan, Ill., assignor to Abbott Laboratories, Chicago, Ill., a corporation of Illinois

Application January 7, 1958, Serial No. 49,165

Term of patent 14 years

(Cl. D1—8)

Fig. 2

Fig. 1

Fig. 3

The broken line representation of the bottle is for illustration only.

I claim:

The ornamental design for a label, substantially as shown and described.
